UNITED STATES PATENT OFFICE.

HENRY GARDINER LLOYD, OF SURBITON, AND CHARLES ALFRED SPON, OF ORPINGTON, ENGLAND.

FLUID-CURRENT MOTOR.

1,413,411.

Specification of Letters Patent. Patented Apr. 18, 1922.

Application filed October 28, 1920. Serial No. 419,603.

To all whom it may concern:

Be it known that we, HENRY GARDINER LLOYD, subject of the King of England, residing at Surbiton, Surrey, England, and 5 CHARLES ALFRED SPON, subject of the King of England, residing at Orpington, Kent, England, have invented certain new and useful Improvements in Fluid-Current Motors, of which the following is a specification.

10 This invention is for improvements in or relating to fluid-current motors and has for one of its objects to provide a simple and efficient means whereby a stream or current of water or other fluid may be employed to 15 drive a motor.

The primary feature of the present invention consists in the combination with means (for instance a projection into a current from a body either fixed or moving relatively to that current,) for producing a vortex, in a current of fluid, of a shaft situated in said vortex, and coincident with or approximately parallel to the axis thereof and vanes on the shaft to be propelled by the 25 rotating vortex. Conveniently, the vortex-producing means may take the form of an abutment arranged to divide the current of fluid and thus produce a vortex on each side of its centre line, and this abutment may 30 be pivoted and carry on its rearward face a stabilizing vane, wholly or partly immersed in the current of fluid, to maintain the abutment in operative position. Conveniently also the shape of the abutment can be controlled to vary its effect.

According to another feature of the invention the vanes on the shaft (and preferably also any arms employed to couple the vanes to the shaft) are formed with 40 pocketed or concaved rearward faces to receive the effort of the rotating vortex, the curve of these faces being such that the said faces shall offer as much resistance as is desired to the movement of the fluid past these 45 vanes and arms.

For a more complete understanding of the invention by way of example only there will now be described a constructional form of fluid-current motor according to the invention, which is illustrated, mainly diagrammatically, in the accompanying drawings, wherein—

Figure 1 is an elevation in section on the line 1—1 of Figure 2;

Figure 2 is a plan in section on the line 55 2—2 of Figure 1; and

Figure 3 is a plan corresponding to Figure 2, and illustrative of a modification.

Like reference numerals indicate like parts in both figures of the drawings. 60

The stream or current employed may be of water or any other suitable fluid, and the motor may be disposed therein horizontally, vertically or at any angle suited to the situation of the axis of the vortex that is to be 65 utilized. In the present example, the axis of the motor is intended to be disposed vertically within the vortex, that is to say, the axis is to be parallel with or co-incident with the axis of the vortex. 70

A standard or support 10 has mounted for rotation on it a base 11 with roller bearings 12 between the two parts. Carried in the ball bearings 13 on the base plate 11 is a shaft 14. The base 11 has secured to it the 75 bottom plate 15 of a hollow abutment 16 of triangular form, having curved sides as shown more clearly in plan in Figure 2. The abutment 16 is closed at the top by a plate 17, and the upper end of the shaft is journaled in a bearing in the plate 16 by means of the ball-bearing 18. It will be seen, therefore that the shaft 14 can revolve independently of the abutment 16 and its top and bottom plates and the abutment 16 can also rotate on the supports 10 independently of the 80 shaft 14. 85

The top plate 17 is provided with a rearwardly extending tail or vane 19, and a counter-balance weight 20. The vane 19 is to be 90 wholly or partly immersed in the operating fluid for the purpose of maintaining the abutment in operative position. The bottom plate 15 carries counter-balance weights 21. 95

The base plate 11 is formed with two divergent radially extending arms, and corresponding arms 22 are secured to the top plate 17. The two latter arms are cross-connected by a plate 23 secured to them near their outer extremities. 100

Secured at or near its extremities between each corresponding pair of the upper and lower radial arms is a spindle 24. Mounted on each spindle 24, by means of upper and lower ball-bearings 25, is a frame comprising 105 upper, central and lower discs 26 which together unite the curved arms or vanes 27 to form what may be described as a paddle-

wheel rotor. Secured to the bottom disc 26 of each rotor is a pulley 28, and each pulley 28 is connected by a band 29 to a pulley 30 mounted on the shaft 14.

5 When the motor described in the foregoing is placed in a moving fluid stream, the directing vane 19 maintains the abutment so that its longer side faces the stream which will constantly travel in the relative direction of the arrow 31 in Figure 1. The abutment splits the stream of fluid and consequently varies the direction and velocity of the latter, producing one or more vortices, in the current. In the present example, it is found that the abutment illustrated will produce two vortices, the centres of which are substantially co-incident with or in the region of the axes of the spindles 24. Each of the rotors is thus disposed in a vortex, and 10 the curved rear face of the abutment 16 assists in the production of the vortices in desired relation to the rotors.

15 The vanes 27 are curved or pocketed to present concave rearward faces to the flow of the vortices produced, and the rotors will rotate in the direction of the arrows 32 in Figure 2. By suitably connecting the belts 29, as shown in the latter figure, to the pulley 30, the turning effort of both rotors will 20 be transmitted in the same sense to the shaft 14 which may be connected with any device that it is desired to drive, for example, an electrical generator.

25 It is obvious that the invention admits of many modifications; for example, instead of employing only one abutment with either one or two rotors, there may be a series of such abutments placed across the stream or current, each producing, say, one or two operative vortices, and the rotor spindles in all 30 these vortices may be coupled to a single main shaft as desired.

35 Moreover, the forward or other face of the abutment described, or each of such abutments, if more than one is employed, may be flexible so that their shape may be varied in order to adjust their vortex-producing effect.

40 Figure 3 diagrammatically illustrates such a construction. In this case the abutment 16 is in the form of a flexible metallic strip to the inner ends of which are pivoted inwardly extending arms 33 terminating in guide rollers 34 between which is disposed a wedge 35. The arms 33 are suitably guided, 45 and it will be seen that on movement of the wedge toward or away from this abutment, the degree of concavity of the latter will be varied. The wedge may be automatically operated by some form of governor driven 50 by the rotor.

55 It is not essential to provide stabilizing or guide-vane such as 19, as the abutment may be arbitrarily fixed in the current or stream, particularly in cases where the direction of flow of the current does not ma-

terially vary from time to time. In cases, however, where the direction of flow of the current does vary, it will be appreciated that the provision of vane such as 19 is desirable.

70 Means may be provided for varying the angle of the vortex-propelled vanes relatively to their shaft in order to control the speed of rotation, or a portion of these vanes may be shielded from the propellant effort of the vortex, say by a hood.

What we claim as our invention and desire to secure by Letters Patent is:—

1. The combination of means for producing a vortex in the current of fluid, a shaft 80 adapted to be situated in said vortex and substantially parallel to the axis thereof, and vanes on the shaft to be propelled by the rotating vortex, substantially as described.

85 2. The combination of means for producing a vortex in a current of fluid, a shaft adapted to be situated in said vortex and substantially coincident with the axis thereof, and vanes on the shaft to be propelled by the rotating vortex, substantially as described.

90 3. The combination with an abutment for dividing a current of fluid and thus to produce a vortex, a shaft to be situated in a vortex thus produced and substantially parallel to the axis of the vortex, and vanes on the shaft to be propelled by the rotating vortex, substantially as described.

95 4. The combination of an abutment for dividing a current of fluid and thus to produce a vortex on each side of the centre line of the abutment, shafts to be situated one in each vortex and substantially parallel to the axis thereof, and vanes on the shafts 105 to be propelled by the rotating vortices, substantially as described.

100 5. The combination with a pivoted abutment for dividing a current of fluid to produce a vortex, a stabilizing vane on the rearward face of the abutment of which vane at least a part is to be immersed in the current of fluid to maintain the abutment in operative position, a shaft situated in the vortex thus produced and approximately 115 parallel to the axis of the vortex, and vanes on the shaft to be propelled by the rotating vortex, substantially as described.

110 6. The combination of means for producing a vortex in a current of fluid, a shaft to 120 be situated in said vortex and approximately parallel to the axis thereof, and vanes on the shaft to be propelled by the rotating vortex, the vanes being formed with pocketed rearward faces to receive the effort 125 of the rotating vortex, substantially as described.

125 7. The combination with a hollow chamber which constitutes means for dividing a current of fluid to produce a vortex, a main 130

shaft carried by the said hollow chamber and rotatable independently of it, a rotor shaft to be situated in said vortex and approximately parallel to the axis thereof, 5 means operatively connected with the said hollow chamber and serving to support the rotor shaft, vanes on the rotor shaft to be propelled by the rotating vortex and means to couple together the rotor and main shafts, 10 substantially as described.

8. The combination with an abutment for dividing a current of fluid and thus to produce a vortex therein, a shaft to be situated in said vortex and substantially parallel to 15 the axis thereof, vanes on the shaft to be propelled by the rotating vortex, and means whereby the shape of the abutment can be controlled to vary its vortex-producing effect, substantially as described.

9. In means for producing a vortex in a 20 current of fluid, a shaft having its axis coincident with the axis of said vortex, and vanes on the shaft to be propelled by the rotating vortex, substantially as described.

10. The combination with an abutment 25 for dividing a current of fluid and thus producing a vortex therein, of a shaft having its axis coincident with the axis of said vortex, vanes on the shaft to be propelled by the rotating vortex, and means whereby 30 the shape of the abutment can be controlled to vary its vortex producing effect, substantially as described.

In testimony whereof we have signed our names to this specification.

HENRY GARDINER LLOYD.
CHARLES ALFRED SPON.
